FUEL PUMP DRIVE FOR DIESEL ENGINES

Richard H. Sheppard, Hanover, Pa.

Application July 9, 1946, Serial No. 682,398

4 Claims. (Cl. 123—179)

1

This invention relates to the starting of Diesel motors and has for its principal object the provision of a mechanism which will insure that the fuel is delivered to the combustion chamber of the Diesel engine at a greater speed than would be had if the starter were directly connected to the fuel pump shaft. As a corollary the invention includes the provision of a spring member in the chain of gearing between the crank shaft of the engine and its fuel pump shaft, particularly one in which power is stored in the spring during a portion of the revolution of the large starting gear and when the spring is released a sharp motion or impulse is given to the fuel pump shaft whereby the fuel is discharged in nearer accord with the manner in which fuel is discharged while the engine is under load.

A still further object of the invention consists in the insertion in a Diesel engine starting mechanism of a quick impulse device which will automatically become inoperative as soon as the engine approaches normal speed.

In the drawings:

Figure 1 is an elevation.

Figure 2 is a vertical section through the axis of the fuel pump shaft.

Figure 3 is a section on line 3—3 of Figure 1.

Figure 4 is a section on line 4—4 of Figure 1.

Figure 5 is a section on line 5—5 of Figure 4.

Figure 6 is an elevation of the cup.

Figure 7 is a detail on line 7—7 of Figure 4.

The fuel pump shaft of the Diesel engine consists, as is usual, of an inner member 10 and an outer member 11, which, while they have relative movement, as far as the present invention is concerned, may be considered as a single member. In any event, the two members invariably rotate together. The outer member turns in a bushing 12 in the fuel pump casing 13 and carries at its end a screw member 15 secured to the fuel pump shaft as by the bolts 16. This extension 15 of the fuel pump shaft turns in a bushing 17 between the screw extension and the timing device plate 19, which itself is fast to the large bushing or bearing 20 secured as by the bolts 21 to the back wall 22 of the gear case.

The member 20 has the usual oil hole 24 and the usual oil outlet 25 and the forward extension, that is, to the left in Figure 2, of the bushing 20, furnishes a bearing as at 26 for the hollow hub 27 of the gear 28 which receives power from the crank shaft 30 through an idler 31.

A cup 33 is permanently secured as by the rivets 34 to a plate 36 fitting snugly the gear 28 and fast to it as by the bolts 37. A retaining nut 39 pre-

vents movement of the gear 28, the plate 36 and the cup 33, away from the fuel pump shaft.

The forward portion 40 of the screw member 15 which may be considered as a part of the fuel pump shaft is slabbed off to afford a seat for the floating washer 41 which fits the stub shaft portion 40, rather snugly, the latter being threaded at its free end to receive the nut 39.

The small washer 46 turns freely on the stub shaft 40 and its function is to prevent too great movement of the pawl 60.

A spring 50 is anchored at one end as at 51 to the washer 41 which always turns with the fuel pump shaft. At its other and larger end the spring 50 is anchored as at 52 to an extending portion 53 of the cup 33. As best seen in Figure 4, the cylindrical flange of the cup is cut away on both sides leaving two extensions 53. The purpose of these two oppositely disposed members 53 is to wind the spring and to release the spring. Within the cup is a driven plate 55 which generally is circular, but has two portions 56 of greater radius and just clearing the inside wall of the flange cup and having its outside arc of exactly the same radius as the outside of the cup. The driven plate 55 may therefore have relative movement of rotation with respect to the cup from one edge 57 of an extension 53 to the adjacent edge 58 of the opposite flange extension 53. A pawl 60 is pivoted as at 61 to the driven plate 55. The larger end 62 of the pawl acts as a weight and holds the shorter arm 63 of the pawl so that it extends beyond the outer margin of the cup 33. A small point 64 on the pawl is merely for convenience in restoring the pawl to operative position when the centrifugal force of rotation throws the heavy arm 62 outward against the inner wall of the flange extension 53 at which time of course the short arm 63 is well within the cup. A fixed spacer 65 is mounted on the plate 55 to extend exactly the same distance as the top of the pivot pin 61 the better to position the real thin washer 67.

A stud 66 is fixed to the timing plate 19 so as to be engaged by the short arm 63 of the pawl as the driven plate 55 rotates. The engagement of the pawl and the stud hold the driven plate against movement and since this driven plate has no relative movement with respect to the fuel pump shaft the latter is held stationary as long as the pawl engages the stop. The driving cup, however, is continuously rotated in counter clockwise direction as seen in Figure 4 and in time the leading edge 58 will make contact with the now stationary pawl and will cam the short end 63 inwardly. The release of this short end of the

pawl which acts as a trigger permits the driven plate 55 to move rapidly forward under the urge of the now tightly wound spring 50 so that the ear 56 of the driven plate catches up to the following edge 57 of the flange extension 53 of the cup. The net result of this action is to give far greater speed of rotation to the fuel pump shaft than would be had if the drive from the crank shaft were constant. Hence, while the fuel discharge is in perfect timing there is in every revolution of the fuel pump shaft one sharp impulse per cylinder and this results in a far more desirable discharge of Diesel fuel to the combustion chamber. Due to the centrifugal effect on the pawl the impulse ceases just as soon as the engine gets up to normal speed as at such time the larger end 62 of the pawl is thrown outward with the point 64 in engagement with the inner surface of the flange extension 53 of the cup 35. Except for the point there would be a danger of the pawl wedging against the cup flange.

I claim:

1. In a device to facilitate the starting of a Diesel engine, a fuel pump shaft, a gear coaxial therewith and adapted to be driven from the crank shaft of the engine, mechanism for connecting the gear with the shaft including a spring connection, means for winding the spring as the gear turns without rotating the shaft, and trip means for releasing the wound spring to rotate the shaft at a higher rate of rotation than the gear after the gear has rotated through a chosen angle of movement, said trip means including a centrifugally controlled member whereby the winding device is rendered inoperative when the gear reaches a chosen speed of rotation.

2. The device of claim 1 in which a plate fast to the shaft carries a pawl which at slow speeds engages a stop, and the gear carries a cup, the spring is fast to the cup at one end and to the shaft at the other end, and a projection on the cup cams the pawl from the stop and frees the plate and shaft so that the spring now wound rotates the shaft.

3. In a device for facilitating the starting of a Diesel engine, a casing, a fuel pump shaft jour-

naled in said casing, a stop fixed to the casing, a plate fast to the shaft and having two extending ears, a pawl pivoted to the plate and having one end movable into engagement with the stop at slow speeds of the plate, a cup coaxial with the shaft and having a flange partly cut away to provide an opening to receive the two ears and the pawl with lost motion in excess of 45°, a spring fast at one end to the cup and connected at the other end to the shaft, means for rotating the cup in timed sequence with the engine shaft, whereby the fuel pump shaft, which is held against movement while the pawl engages the stop and the cup winds the spring, is driven at a more rapid rotation than that of the cup by the transfer of stored power in the spring when the flange cams the pawl from the stop, thus freeing the shaft and permitting the spring to unwind.

4. In a device for facilitating the starting of a Diesel engine, a fuel pump shaft, a gear rotating in fixed relation to the engine shaft, and means for transferring power from the gear to the fuel pump shaft including a spring connection alternately wound and released, to give a series of quick impulse movements to the fuel pump shaft while the engine is being started, whereby in starting the engine, the fuel is delivered at a greater speed than if the fuel pump shaft were directly connected to the gear, and thus the fuel is delivered in starting in sharp impulses corresponding more nearly to the manner in which the fuel is delivered while the engine is under load.
